(57) **CLAIM**

The ornamental design for top rail corner piece, as shown
and described.

DESCRIPTION

FIG. 1 is a perspective view of a top rail corner piece for a
tote box showing my design. The broken line showing of the
tote box is for illustrative purposes and forms no part of the
claimed design.

FIG. 2 is a top plan view thereof;

FIG. 3 is a front elevational view thereof (left side view is
a mirror image thereof);

FIG. 4 is a rear view thereof (right side view is a mirror
image thereof); and,

FIG. 5 is a bottom view thereof.
